UNITED STATES PATENT OFFICE.

GEORG HIETZGERN, OF KREMS, AUSTRIA.

MACHINE FOR HERMETICALLY CLOSING PRESERVE JARS.

Application filed March 17, 1926, Serial No. 95,399, and in Austria March 20, 1925.

This invention relates to a machine for securing hermetic closures to jars of glass, earthenware or the like, of that class wherein the hermetic closing of the jar is effected by 5 axially pressing downwards a closure upon the open end of the jar, an inturned ring of such closure engaging the bottom side of the flange of the open end of the jar.

One object of the invention is to avoid 10 breakage of the jar, as in the known machines, caused by the engagement of rigid linkage with the closure during the closing operation.

With this and other objects in view my invention consists in arranging a spring between 15 the jar supporting plate and an adjustable element of the machine, a second spring being interposed between the closure pressing head and its driving linkage, such spring being stronger than that interposed 20 between the said jar supporting plate and the said adjustable element of the machine.

In the accompanying drawing:

Figure 1 shows a form of cap as used in this invention;

25 Figure 2 is a view partially in section and partially in elevation of an open end of a jar with a cover and ring applied thereto;

Figure 3 is a side elevation and

30 Figure 4 is a front elevation partly in section of a machine for securing the closures; and

Figure 5 is a plan view of the die carrier.

The closure consists of cover 1 preferably of sheet metal and a packing ring 2 of some 35 elastic material, preferably rubber. This packing ring may be dispensed with if the cover be made of a yielding material such as waterproof paste board. 3 is the ring, the inturned top edge of which engages with the 40 top face of the cover and the bottom edge of which is provided with notches 4, triangular in shape, the side edges of which converge upwardly. The numeral 5 represents tongues left between successive notches.

45 The machine for making the closure is constructed as follows: The base plate 6 of the machine is provided with bolt holes 7 for securing it to a suitable support. A bracket 9 secured to the machine frame 8 carries the female thread for a hollow screw spindle 10 supporting a jar carrier 13 on which is placed the jar 14 to be closed, a buffer spring 12 being interposed between the jar carrier 13 and the spindle 10. The jar carrier 13 is 50 guided by a rod secured to it and passing

through the hollow spindle. The buffer spring bears against a plate 15 secured to the top end of the spindle. A hand wheel 16 at the bottom end of the spindle serves for adjusting vertically the jar carrier 13.

60 A die carrier 18 is secured by two screws 19 to the base plate 6 which is provided with a large slot 17. Preferably the die carrier and the die are divided axially and the movable half of the die carrier is hinged to its 65 stationary half as at 20. The movable half is permanently acted upon by a spring 20' tending to open the die carrier. For closing the die and keeping it closed the movable half of the die carrier is provided with a 70 handle 21 having a projection 22 with which engages a hook 23 pivoted to the stationary half of the die carrier. This hook forms one arm of a bell crank lever the second arm 24 of which extends upwards and is provided 75 at its end with a knob 25. A leaf spring 29 acts on the rear side of the arm 24 in such a manner that it tends to always keep the hook 23 in the closing position.

Centrally above the die 18' is mounted in 80 the frame of the machine a guide 26 for a rod 27 the bottom end of which carries the pressing head 28 provided with a lateral projection 30' to which an arm 30 is pivoted. The arm 30 carries at its pivoted end an extension 31 adapted to engage the bottom side 85 of the projection 30' so that the arm 30 can turn in an upward direction only.

A spring 32 tends to return the arm 30 into its horizontal position. The arm 30 is so 90 arranged that when the pressing head moves downward it strikes against the knob of the bell crank lever 24 and turns upward overcoming the action of the spring 32.

95 In order to prevent an accidental downward movement of the pressing head, for instance, owing to the gravity as well as any turning of the same, the guide rod 27 is provided with a groove against which a metal strip or a plate spring 27' is forced by screws 100 26' arranged in the guide 26. The rod 26 carries above the rod 27 a counter plate 33 against which bears a buffer spring 34 stronger than the spring 12 and engaging a sleeve 35 sliding on the rod 27. For limiting 105 the upward movement of this sleeve the guide rod 27 is provided at its end with a nut and a counter nut 36. The sliding sleeve is engaged by a pair of links 37 by which the upward movement of a hand lever 38 pivoted to the 110

guide 26 is transmitted by the sliding sleeve and the buffer spring 34 to the pressing head.

The operation of the machine is herein-after described.

- 5 The jar carrier 13 is adjusted to the required position by the hand wheel 16 and the screw spindle 10 so that the flange 40 of the open end of the jar 14 with the packing ring, if used, the cover 1 and the sheet metal ring 10 3 slightly projects above the die 18'. Then the open die carrier is brought into the closed position and the pressing head is forced downwards by the actuating lever 38. The buffer spring 34 being stronger than the 15 spring 12, supporting the jar carrier 13 and the jar 14, at first the jar together with the closure are forced downwards and then the tongues 5 of the ring 3 are bent inwards and upwards so as to form the lower half of a 20 torus, the inner edge of which engages into the angle 41 between the flange 40 and the neck of the jar 14 as clearly shown in Fig. 2. As the pressing head descends the pivoted arm 30 strikes against the knob 25 of the bell 25 crank lever 23, 24 and is turned upwards without actuating the bell crank lever. When the pressing head moves upwards the arm 30 strikes against the bottom side of the knob 25 and pushes it aside, since the arm cannot 30 yield being prevented from yielding by its extension 31 engaging with the bottom side at the projection 30'. Thereby the hook 23 is turned and the die carrier 18 is opened. The jar thus closed can thus be removed 35 from the front side of the table and a fresh one may be brought into position.

The machine above described is very simple and efficient and requires only a comparatively small amount of power. In some cases 40 of sterilizing fruits, etc. it is necessary to expel the air after the closing cap has been put on the jar, but before the closure has been finally completed. With the present machine such method of closing jars is effected very rapidly, and with a smaller amount of power. Before operating the machine the die carrier is opened and a die is introduced, the upper surface of which is cone-shaped, the top of 45 the cone being below the base. A jar is now introduced into the machine, a closing cap is put on the jar, the die carrier with the die is closed, and the pressing head is moved downwards. Due to the form of the die the tongue 50 of the cover or the ring are not fully bent inwards and upwards so as to form the lower half of a torus, but are only bent under an angle of 45° against the side wall of the jar, according to the form of the surface of the die. As the inner edge of the tongues of the 55 cover of the ring does not engage the angle (41) between the flange (40) and the neck of the jar (see Fig. 2), but only the outer surface of the jar neck with a slight friction, the cover will act as a valve during the 60 subsequent heating and sterilization. Dur-

ing heating, the expanding steam and the expelled air raise the cover and escape between the tongues of the cover. During cooling of the jar the slight vacuum in the jar draws the cover downwards, so that the cover is pressed 70 upon the opening of the jar. The die carrier is now opened and the first die is replaced by a die for complete closing of the jar illustrated in the drawings. After inserting the jar treated in the described manner into the machine, the pressing head is pressed downwards and the closing of the jar is completed as by the die shown the tongues of the ring being fully bent inwards and upwards so that the inner end of the 80 tongues engage into the angle between the flange and the neck of the jar. Now any raising of the cover is prevented.

The present machine necessitates only the use of unskilled labor and is also much 85 cheaper than the old machines and the present machine may be readily adjusted for different sizes of jars by simply exchanging the dies.

What I claim is—

1. In a machine for applying hermetic closures to jars the combination of jar supporting means comprising a vertically adjustable element, a jar supporting plate and a spring interposed between such jar supporting plate 90 and adjustable element, a die carrier made in two parts hinged together one of said parts being stationary, a spring actuated releasable locking device adapted to keep the die carrier in closed position, a divided die supported by such die carrier and adapted to enclose the jar neck with the closure placed thereon, a pressing head adapted to engage the said closure, means for moving the said pressing head axially relatively to the said die, a spring interposed between such pressing head and the said moving means, such spring being stronger than the spring interposed between the said vertically adjustable element and the said jar supporting plate 105 and means operatively connected with the pressing head for releasing the said locking device.

2. In a machine for applying hermetic closures to jars, the combination of jar supporting means comprising a vertically adjustable element, a jar supporting plate and a spring interposed between such jar supporting plate and adjustable element, a die carrier made in two parts hinged together one of said parts 110 being stationary, a spring actuated releasable locking device adapted to keep the die carrier in closed position, such locking device comprising a bellcrank lever, one arm of such lever being hook-shaped and adapted to keep the two parts of the die carrier closed, the other arm of such lever being provided with a knob, a divided die supported by such die carrier and adapted to enclose the jar neck 115 with the closure placed thereon, a pressing 120 device adapted to engage the said closure, means for moving the said pressing head axially relatively to the said die, a spring interposed between such pressing head and the said moving means, such spring being stronger than the spring interposed between the said vertically adjustable element and the said jar supporting plate 125 and means operatively connected with the pressing head for releasing the said locking device.

head adapted to engage the said closure, means for moving the said pressing head axially relatively to the said die, a spring interposed between such pressing head and the said moving means, and means operatively connected with the pressing head for releasing the said locking device.

3. In a machine for applying hermetic closures to jars, the combination of jar supporting means comprising a vertically adjustable element, a jar supporting plate and a spring interposed between such jar supporting plate and adjustable element, a die carrier made in two parts hinged together one of said parts being stationary, a spring actuated releasable locking device adapted to keep the die carrier in closed position, a divided die sup-

ported by such die carrier and adapted to enclose the jar neck with the closure placed thereon, a pressing head adapted to engage the said closure, means for moving the said pressing head axially relatively to the said die, a spring interposed between such pressing head and the said moving means, and means operatively connected with the pressing head for releasing the said locking device, 20 said means comprising a spring-actuated pivoted arm, and means whereby such arm is turned when the pressing head descends but is immobile to actuate the release of the locking 25 device when the pressing head rises.

In testimony whereof I have signed my name to this specification.

GEORG HIETZGERN.
